Primary Examiner — Catherine Ho

(57) **CLAIM**

The ornamental design for an automatic vending machine of skibobs, ski bikes, snow bikes, snow scooters, ski trikes, mountain bikes, mini-velos, and kick scooters, as shown and described.

DESCRIPTION

1. Automatic vending machine of skibobs, ski bikes, snow bikes, snow scooters, ski trikes, mountain bikes, mini-velos, and kick scooters
2. Automatic vending machine of skibobs, ski bikes, snow bikes, snow scooters, ski trikes, mountain bikes, mini-velos, and kick scooters

1.1: Front

1.2: Back

1.3: Top

1.4: Bottom

1.5: Left

1.6: Right

1.7: Top left perspective

1.8: Top left perspective in an alternate configuration

2.1: Front

2.2: Back

2.3: Top

2.4: Bottom

2.5: Left

2.6: Right

2.7: Top left perspective

2.8: Top left perspective in an alternate configuration

The broken line showing of automatic vending machine of skibobs, ski bikes, snow bikes, snow scooters, ski trikes, mountain bikes, mini-velos, and kick scooters is for the purpose of illustrating portions of the article and forms no part of the claimed design.
